US0D1107689S

(12) **United States Design Patent** (10) **Patent No.:** **US D1,107,689 S**
(45) **Date of Patent:** **** Dec. 30, 2025**

(54) **CASE**

- (71) Applicant: **Urban Armor Gear, LLC**, Laguna Niguel, CA (US)
- (72) Inventors: **Raymond Lee**, North Point (HK); **Eric Yoshinari**, Laguna Niguel, CA (US)
- (73) Assignee: **Urban Armor Gear, LLC**, Laguna Niguel, CA (US)
- (**) Term: **15 Years**
- (21) Appl. No.: **29/958,541**
- (22) Filed: **Aug. 20, 2024**

(57) **CLAIM**

The ornamental design for a case as shown and described.

DESCRIPTION

FIG. 1 is a perspective view of a case of our design.

FIG. 2 is a front view of the case of FIG. 1.

FIG. 3 is a back view of the case of FIG. 1.

FIG. 4 is a first side view of the case of FIG. 1.

FIG. 5 is a second side view of the case of FIG. 1.

FIG. 6 is a top view of the case of FIG. 1; and,

FIG. 7 is a bottom view of the case of FIG. 1.

The broken lines shown in the figures are included for the purposes of illustrating portions of the case and form no part of the claimed design. Randomly dashed lines represent surface shading. The long dash-short dash-long dash-short dash lines illustrate boundaries that form no part of the claimed design.

1 Claim, 5 Drawing Sheets
